WEFT REPLENISHING LOOM

Clifford Darwin, Worcester, Mass., assignor to
Crompton & Knowles Loom Works, Worcester,
Mass., a corporation of Massachusetts

Application October 23, 1943, Serial No. 507,394

16 Claims. (Cl. 139—232)

This invention relates to weft replenishing looms and it is the general object of the invention to provide a loom wherein several stacks of bobbins can be used for the replenishment of a single shuttle while another stack is used for replenishing a second shuttle.

Certain types of fabrics require wefts of two different kinds, one which is consumed rapidly in the weaving operation while the other is consumed at a relatively slow rate. In order that the loom may operate for a considerable length of time with a single filling of the magazine, two or more stacks are assigned to the rapidly consumed weft while a single stack is used for the other weft. In such a magazine it is necessary to make provision for distributing the selections of bobbins from the group of stacks so that the stack will be depleted uniformly.

In certain types of looms to which such mechanisms have been applied it has been customary to control the selector for the several bobbin releasers by mechanism including opposed springs, one spring acting on the selector and the other spring providing a yielding connection between the shifting shuttle box mechanism and the selector. It is an important object of my present invention to provide position controlling devices between the shifting shuttle box mechanism and the selector permitting the latter to assume two or more positions for one position of the shuttle boxes by means of a collapsible connector between the selector and its control mechanism.

In the simplest and preferred form of my invention three stacks of a four-cell magazine are provided with coarse weft and one stack with fine weft and the color selector for the bobbin releasers of the several stacks is moved into registry with the one stack by connections from the shuttle box mechanism but is permitted to register with any one of the three stacks of coarse weft by means of a cam. In this feature of my invention the selector is urged forwardly by a compression spring in the aforesaid connector which yields varying amounts depending upon the position of the cam.

As heretofore constructed it has been customary to move the selector rearwardly by a positive connection from the shuttle boxes so that when the selector is shifting from registry with the front to the back stack it is acted upon by a positive force derived from the box mechanism. It is because of this condition that it has heretofore been necessary to use the opposed springs already mentioned. In my present invention I reverse the direction of the positive force so that the selector

is urged forwardly by a force derived from the shuttle box mechanism and transmitted through the collapsible connector. This reversal permits me to use a spring to move the selector rearwardly and there is no need for a spring in the box motion connection.

In the modified form of my invention the parts are altered to permit the selector to register with the front two stacks under cam control and in addition register selectively with either of the rear two stacks. In this arrangement of my invention three shuttles are used one of which has coarse weft to be replenished by the front pair of stacks while the other two shuttles are replenished with distinctive weft from the rear stacks. In this second setting of my invention the moving force for the selector derived from the shifting shuttle box mechanism corresponds to a two-stack shift so that when the shuttle boxes have a one box shift the selector will shift from registry with the first stack to registry with the third stack. When the shuttle boxes shift to place the third shuttle in active position there is a further rearward movement of the selector tending to move the latter through a second two-stack shift. Since there are only four stacks in the magazine it is necessary to arrest movement of the selector when it has reached registry with the fourth stack and compensate for the remainder of this second two-stack shift by some form of lost motion connection. This lost motion is very conveniently provided by moving the box motion lifter cams for the selector control mechanism to a position out of engagement with the control mechanism.

Whether the loom operates with two or three shuttles, the connections between the shifting shuttle box mechanism and the selector will be the same, the only difference being an adjustment in the position of the collapsible connector relatively to the selector. Furthermore, the loom can readily be converted to weave with four different colors without altering the connections between the box motion and the selector.

With these and other objects in view which will appear as the description proceeds, my invention resides in the combination and arrangement of parts hereinafter described and set forth.

In the accompanying drawings, wherein a convenient embodiment of my invention is set forth, Fig. 1 is a side elevation viewed from the center of the loom of a multi-stack weft replenishing mechanism having my invention applied thereto,

Fig. 2 is a vertical section on an enlarged scale on line 2—2 of Fig. 1.

Fig. 3 is a detailed elevation of part of the mechanism shown in Fig. 1 setting forth the positioning cam used with the preferred form and showing the selector lever and connector set in position for using the same kind of weft in the first three stacks of the magazine.

Figs. 4, 5 and 6 are enlarged longitudinal sections through the collapsible connector showing it in different positions.

Fig. 7 is a fragmentary elevation of a part of the mechanism shown in Fig. 1 in a different position, and on an enlarged scale.

Fig. 8 is a diagrammatic view showing the connections between the shifting shuttle box mechanism and the selector and indicating the shifting shuttle boxes.

Fig. 9 is a view similar to Fig. 7 but showing the cam used with the modified form of the invention, and

Figs. 10, 11 and 12 are diagrammatic views of the modified form showing the selector and control parts therefor in different positions.

Referring particularly to Fig. 1, the loom frame 10 comprising a breast beam 11 on which is mounted the frame of the usual multi-color weft replenishing mechanism M. In the present instance the mechanism M accommodates four vertical stacks of reserve bobbins designated generally at 12, 13, 14 and 15. These stacks of bobbins are provided with the usual bobbin releasing cradles designated generally at 16 operated by vertically reciprocable slides or releasers 17, 18, 19 and 20.

A selector 22 for the releasers is mounted on a horizontally sliding rod 23 and has front and back releaser operating fingers 24 and 25, respectively. The selector is capable of having four longitudinal positions in each of which its fingers will register with one or another of the bobbin releasers. The latter are normally down but are raised preparatory to bobbin release and subsequently depressed to complete release, whereupon the affected bobbin will descend to a common transfer position under transerrer arm 26.

The upper part of the magazine is provided with a horizontal rocking shaft 30 the forward end of which is connected by arm 31 to a descending rod 32 operatively connected as at 33 to the normally inactive transfer latch 34 pivoted on the transerrer arm 26. A shelf 35 secured to the shaft 30 is normally in raised position but when one or another of the vertical slides is raised an operating dog 36 thereon extends over the shelf 35 and upon subsequent depression of the raised slide this dog engages and lowers the shelf, thereupon rocking the shaft 30 in such a direction as to depress rod 32 and lift the latch 34 into the path of a transfer bunter 37 on the lay L.

The resetting mechanism for the shaft 30 and shelf 35 comprises a thread cutter and shuttle feeler 40 pivoted as at 41 to the magazine frame and connected to an upwardly extending rod 42 attached to an arm 43 secured to shaft 30. The lower end of the thread cutter and shuttle feeler 40 is normally in the forward position shown in Fig. 1, but when the shelf 35 is depressed rod 42 is raised and the head 45 of the thread cutter is projected rearwardly while the lay is in its back position. As the lay advances it strikes the head 45 and moves it forwardly, thereupon depressing rod 42 and returning the shaft 30 to its normal position with shelf 35 raised.

The loom is provided with the usual weft

detector designated at D controlling a pin 50 movable into and out of the path of a lever 51 which floats on a vertically reciprocating bar 52. A rod 53 extends upwardly from one end of the lever 51 and is attached as at 55 to a web 56 extending longitudinally of and forming part of the selector 22. Under normal conditions when sufficient weft is present in the shuttle S' during the detecting interval lever 51 descends idly due to the fact that pin 50 is moved forwardly by the detector D. When exhaustion of weft is indicated, however, the pin 50 remains in the path of lever 51 and the latter upon downward movement of the bar 52 causes rocking of the selector in such a direction as to raise its fingers and cause elevation of that releaser registered with the selector. This operation occurs when the shuttle is at the magazine end of the loom, and at a later time in the operation bar 52 is raised to give the selector 22 an opposite rocking movement to lower its fingers and thereby depress any previously raised releaser registering with the selector. The downward movement of the fingers 24 and 25 which lowers the releasers occurs regularly at two-pick intervals when the shuttle is at the drop box end of the loom opposite the magazine.

In addition to the rocking movements already described the selector has a longitudinal movement transmitted to it through a grooved collar 60 secured to the rear end of rod 23 and receiving a lug 61 on the upper end of a lever 62 pivoted as at 63 to the magazine frame. Lever 62 is provided with a roll 65 to engage the rear part of a cam C for the preferred form, or C' for the modified form of the invention. These cams are mounted for rotation one at a time on a stud 67 secured to the magazine frame and will be further described hereinafter.

Secured to the cam is a ratchet wheel 70 rotatable on the stud 67 and having in the present instance six teeth for engagement with a pawl 71 pivoted to a lever 72 mounted for rocking movement relatively to the magazine frame as at 73. A pivotal connection 74 between the pawl and the lever 72 permits movement of the pawl relatively to the lever away from the cam and against the action of a light tension spring 75 which tends to hold the pawl toward the ratchet wheel. A yieldable lock roll 76 and lock wheel 77 is secured to the ratchet and cam serves to hold them in the several angular positions which they may occupy. If desired a shield 78 may be pivoted on the stud 67 and be connected by link 79 to lever 62. The shield occupies four positions corresponding to the four positions of lever 62 as the latter moves with the selector to its four positions. In the preferred form the shield is out of the path of the pawl for three of these positions, link 79 fitting into hole 80 in shield arm 81 for the purpose. In the modified form link 79 fits a hole 82 in arm 81 and is in shielding position relatively to the pawl for the last two positions.

Shaft 30 carries an arm 85 pivoted to the top of a depending rod 86 connected to lever 72. Down motion of rod 86 when the magazine is set for transfer lowers lever 72 and pawl 71, and subsequent resetting of the magazine causes up motion of the pawl to rock the ratchet wheel and cam secured to it one-sixth of a turn.

The matter thus far described, except cam C' and link 79 and hole 82 in arm 80, closely follows well-known mechanism heretofore used in automatic shuttle box looms operating with several shuttles which become active one at a time and are picked toward and away from that end of the

lay under the magazine M. Whenever the detector indicates weft exhaustion one of the releasers will be raised and thereafter lowered to set the magazine for transfer, this setting involving lifting of the latch 34 to transfer position, movement of the shuttle feeler 40 rearwardly, and lowering of pawl 71. When the magazine is reset the pawl will be given an operative upward movement, provided the shield is in non-shielding position, to turn the cam through 60° as the shaft 30 returns to normal position. I do not wish necessarily to be limited to the particular means shown for operating the pawl 71, but it has proved convenient and causes an advance movement of the cam for each replenishing operation which is called regardless of whether the called transferring operation is completed.

In carrying the preferred form of my present invention into effect I provide means by which the selector 22 can be controlled jointly by the cam C and the gang of shifting shuttle boxes B shown diagrammatically in Fig. 8 for the replenishment of two shuttles. The gang has box cells 90, 91, 92 and 93, but only the top two cells are used, being occupied by shuttles S' and S2, respectively. A lever 100 is pivoted as at 101 with respect to the loom frame and has three arms the lower of which 100a is connected to a tension spring 102 anchored to the loom and the rear arm 100b of which is pivoted to a depending rod 103. The upper arm 100c is attached to a connector 105 of special construction shown more particularly in Figs. 4, 5 and 6. This connector comprises a rod head 106 pivoted to the arm 100c as by a stud 107. The rear end of a rod 108 is threaded into the rod head while its forward end projects into a sleeve 109. The sleeve has a head 110 mounted on a stud 111 extending through a slot 112 of lever 62 and held in adjusted position along the length of the slot in any approved manner. A pin 113 extends across the sleeve 109 and through a radial slot 114 passing through the rod 108. The end of the rod at the right hand end of slot 114 as viewed in Fig. 4 is normally held against pin 113 by a compression spring 115 housed within the sleeve and having the right end thereof bearing against the head 110. The rod 108 can move toward the head 110 against the action of spring 115 as will be described hereinafter.

The position of lever 100 is determined by mechanism connected to the rod 103 and may be similar to that shown in Palmer and Gordon Patent No. 2,238,520. Extending across the loom is a shaft 120 having an arm 121 connected to the lower end of rod 103 at the magazine end of the loom, and having an arm 122 connected to a link 123 at the opposite or drop box end of the loom. For convenience link 123 is shown as pivoted to a lever 124 positioned to engage front and back cams 125 and 126 connected to box shifting mechanism not shown which determines the position of the shifting shuttle boxes B through the box lifter lever 127. These cams are given half rotations by the box shifting mechanism and each cam has a high dwell 128 and a low dwell 129. The spring 102 serves to exert a downward force on rod 103 and therefore tends to hold the lever 124 against the cams, while the latter lift the rod 103 against the action of the spring to rock the lever 100.

In the operation of the preferred form of the invention it may be assumed that the selector 22 is in the extreme forward position shown in full lines in Fig. 8 due to the fact that box 90 and

shuttle S' are active and the high dwells of the cams have lifted the lever 124 and have therefore rocked lever 100 to the right or full line position. When in this position the connector 105 is fully extended as shown in Fig. 4 because of the fact that the cam C has a low dwell 130 thereof under roll 65. As shown more particularly in Fig. 3 the cam has a high dwell 131 of an angular length corresponding to two feeding motions of the ratchet wheel, has two intermediate dwells 132 each corresponding to one feeding motion of the ratchet, while the low dwell is of similar angular length to dwell 131. The roll 65 is held by spring 115 against the low dwell at the beginning of operations and it is for this reason that the selector 22 registers with the front bobbin releaser 17.

When a replenishing operation occurs releaser 17 will be reciprocated in the usual manner and the resetting of the magazine will give the pawl 71 a working stroke to advance cam C one-sixth of a turn. Under these conditions the shield 78 is held in idle position, and as the cam turns one of its intermediate dwells moves the roll 65 to move lever 62 rearwardly, thereby moving the shield toward but still out of shielding position and at the same time moving the selector 22 into register with releaser 18. The next replenishing operation therefore effects reciprocation of the releaser 18 and serves by another rocking of the cam by pawl 71 to register the selector with the releaser 19 as the high dwell 131 moves under roll 65. Under these conditions the shield is still in non-shielding position because of the fact that link 79 is located in the rear hole 80 of the arm 81.

Subsequent replenishing operations of the loom involving the front three stacks of the magazine will move the cam C successively by progressive movements similar to those already described, the fourth transfer drawing another bobbin from the third stack 14, the fifth transfer drawing a bobbin from stack 13, and the sixth transfer returning the selector 22 to its front position so that another bobbin can be drawn from stack 12. In this way the stacks 12, 13 and 14 supply two bobbins each for the replenishment of shuttle S' during a six transfer cycle occurring when the parts are in the position shown in Fig. 8 with rod 103 raised.

It is to be understood that as the cam moves lever 62 rearwardly the spring 115 in the collapsible connector 105 will undergo compression, being in the position shown in Fig. 5 when the selector registers with releaser 18 and being in the position shown in Fig. 6 when the selector registers with releaser 19. When the selector starts its forward motion spring 115 expands and registers the selector with the front two releasers as the cam C continues to turn.

In the foregoing operation it has been assumed that all of the replenishing operations involve the coarse or predominant weft with which stacks 12, 13 and 14 are supplied. The pattern may, however, call for activity of shuttle S2 at any time independently of the position of cam C, in which case the upward shifting of the gang B to place box 91 in action will be accompanied by a rocking of cams 125 and 126 through a half revolution the effect of which is to lower lever 124 through a space corresponding to a one-box shift. The leverage of the connections between the levers 124 and 62 is such that the one-box shift of lever 124 corresponds to a three-space shift of the selector 22. Therefore the lever 100 moves to its rearmost dotted line position of Fig. 8 and the

lever 62 as well as the selector move to their extreme rearward position with the selector registered with releaser 20. The leverage referred to is a three to one ratio and is accomplished in part by having the stud 111 near the lower end of slot 112. When the parts are in the position shown in dotted lines in Fig. 8 shuttle S2 will be replenished from stack 15. The pin 113 is at the forward end of slot 114 during this last operation due to action of spring 115 and as lever 100 is rocked to its rearmost position by spring 102 the lever 62 is moved backwardly by a force transmitted positively through the telescopic link 105. If the shift of the selector is from registry with releaser 17 to releaser 20 there will be no change in the position of spring 115, the connector 105 moving rearwardly without relative change of its parts as though it were a solid connector. If the shift is from releaser 18 or 19 to releaser 20 there will first be an expansion of the spring 115 from the position of Fig. 5 or 6, as the case may be, until the position shown in Fig. 4 is established, after which rearward movement of the connector 105 will proceed as though it were solid. Thus it will be seen that when the selector registers with releaser 20 there is no deformation of spring 115. In mechanisms of this general type heretofore used there has always been a spring which was subjected to deformation, usually expansion, during rearward movement of the selector, and this difference is an important feature of my present invention.

It is to be understood that when the selector is in register with the releaser 20, the lever 62 will have moved rearwardly far enough to move the shield 78 into such position as will prevent the pawl from turning the ratchet when the magazine is reset after a replenishing operation involving bobbins from stack 15. In this way the order in which bobbins are drawn from the front three stacks is not interrupted by a transfer from the rearmost stack. This feature is shown in Turner Patent No. 2,291,997, and in itself is not new except in so far as the shield is controlled through connector 105.

In the modified form of my invention I make provision by which the front stacks 12 and 13 provide the same kind of weft for the replenishment of one shuttle and each of the rear stacks 14 and 15 provide distinctive weft for the replenishment of two other shuttles so that the modified form of the invention is concerned with the replenishment of three different shuttles from four stacks of bobbins in the magazine. This form of the invention is illustrated more particularly in Figs. 9 to 12 but the greater part of the mechanism involved is the same as that employed for the preferred form.

The cam C is replaced by a cam C' having three high dwells 150 between which are located the low dwells 151. This cam C' is therefore able to give the lever 62 only two positions. The stud 111 is moved upwardly in the slot 112 a sufficient distance so that the multiplication of the motion received from lever 124 is in the ratio of two to one. In addition to these changes there will be a third shuttle S3 which will occupy the box 92, and link 79 will occupy hole 82 in arm 81.

In the operation of this modified form the connections from the box motion cams will be in the positions illustrated diagrammatically in Figs. 10 to 12. When shuttle S' is active the gang of boxes B will be in lowest position and this will correspond to Fig. 10 where the high parts of cams 125 and 126 are under the lever 124. The

rod 103 is therefore in its extreme upward position and the selector 22 will register with the front bobbin releaser 17 when a low dwell 151 is under roll 65. Because of the collapsible connector 105 the selector can also register with the releaser 18 when a high dwell 150 is under roll 65. Shuttle S' can therefore be replenished from bobbins drawn from stacks 12 or 13 and the selection for such transfer occur alternately between these two stacks so that they are uniformly depleted for successive replenishing operations involving the shuttle S'.

When it is desired to weave weft corresponding to shuttle S2 the box gang B will rise one space and there will be a corresponding change in the position of cam 125 from that shown in Fig. 10 to that of Fig. 11 so that its low dwell engages the right or forward end of lever 124. There is a corresponding down motion of connector 103 induced by spring 102 equivalent to a one-piece box shift, but since the stud 111 is located as already described, lever 62 will be given a movement equal to a two space shift of the selector and the latter will register with releaser 19. Shuttle S2 can therefore be replenished by bobbins derived from stack 14.

When shuttle S3 becomes active both cams 125 and 126 are given half turns and lever 124 has a further downward motion because of the fact that the connection between link 123 and lever 124 is nearer cam 126 than it is to cam 125. If lever 124 followed the cams 125 and 126 as the latter move from the position of Fig. 11 to that of Fig. 12, lever 62 would move the releaser 22 to the left out of register with releaser 20 under action of spring 102. The stop 155, however, serves to locate the selector 22 in register with releaser 20 as the cams change from the position in Fig. 11 to position of Fig. 12, but before the change is completed. After selector 22 has engaged the stop the cams continue to turn, but lever 124 cannot continue its downward movement because of the stop and one or another of the cams will therefore be located below and out of contact with the lever. In Fig. 12 the rear part of lever 124 is shown as located above the cam 126, but this is only one of the conditions which may exist, inasmuch as the forward end of the lever may be out of contact with cam 125, or both ends of the lever may be out of contact with their respective cams. It will be noted that the connections from the lever 124 up to the selector 22 are not subjected to strain other than that arising from spring 102, cams 125 and 126 being temporarily out of control of the lever 124. This is a significant difference over construction heretofore employed and is another important feature of my invention. When the parts are in the position shown in Fig. 12 shuttle S3 can be replenished from the bobbins in stack 15.

Since link 79 is in hole 82, the shield is in non-shielding position when the selector registers with releasers 17 and 18, but when lever 62 has moved to register the selector with releaser 19, the upper part of the shield disables the pawl 71, and when lever 62 moves to register the selector with releaser 20 the lower part of the shield disables the pawl 71. By this shift of the link 79, therefore, to the right hand hole 82 in arm 81, transfers involving bobbins in the distinctive stacks 14 and 15 do not alter the position of the cam C', and when the shuttle S' again becomes active the selector will be registered with the releaser 17 or 18 with which it previously registered and there will be no inter-

ruption in the alternate drawing of bobbins from the front pair of stacks. As is true in the preferred form of my invention, the shield is not essential to the operation of all features of my invention, but it is desirable inasmuch as it permits the use of the full capacity of stacks 12 and 13 for the replenishment of shuttle S'.

When the loom is to be adapted for weaving with four colors as is usual in looms of the type to which my invention applies, the stud 111 will be given a further upward movement in the slot 112 so that there will be no multiplication of the movement derived from lever 124, and the ratio between the movement of the selector and the lever 124 will be one to one. Under these conditions the cams C and C' will be removed and the selector 22 will be registered with the four bobbin releasers by a control derived solely from lever 124 without modification by any cam. When the magazine is thus set for replenishing four distinctive colors, the connector 105 will operate as though it were solid. In this last setting of the magazine, and also in the setting for the preferred and modified forms of the invention, the effect of spring 115 is to exert a left hand movement on lever 100, but this is the same kind of movement which is induced by spring 102. When the spring 115 is under compression it exerts its force through lever 100, rod 103 and link 123 to the lever 124 and thence to the cams 125 and 126 without being opposed to the spring 102. This relationship whereby the springs are not opposed to each other is a significant feature of my present invention.

From the foregoing it will be seen that I have provided means for converting the usual four-color automatic weft replenishing loom so that one shuttle carrying predominant weft can be replenished from two or three cells of the magazine, and that one or two shuttles can be used for fancy stripe effects, being replenished either from cell 20, or cells 19 and 20. It will further be seen that the collapsible connector 105 permits the selector to assume positions in register with releasers 18 or 19, or both, without opposing its force to spring 102 because of the fact that cams 125 and 126 take the downward thrust of rod 103. Furthermore, it will be seen that when the magazine is set to operate according to the modified form of the invention the cams 125 or 126 merely move out of engagement with the lever 124 upon engagement of the selector with its stop without requiring any compensating feature of the connections between levers 124 and 62. It will also be noted that the magazine is readily convertible to four-color automatic weaving merely by removal of the cams C and C', the collapsible connector 105 in such setting serving as a solid connector. For this last conversion it may be simpler to remove the ratchet wheel, lock wheel and cam all of which are constructed as a unit mounted on stud 67, and also disconnect the pawl 71.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a plurality of stacks of reserve bobbins and operating with two shuttles one of which is replenished from a group of said stacks and the other of which is replenished from one of said stacks, a selector to register with said stacks one at a time,

an actuator for said selector having one position when one of said shuttles is active and having a second position when the other shuttle is active, and positioning mechanism for said selector including a telescopic member operatively connected to the actuator and causing said selector to register with said one stack when the actuator is in said one position, and a stop forming part of said positioning mechanism and having steps, one for each stack in said group, and capable of determining with which stack in the group said selector shall register when the actuator is in said second position and also determining the extent to which the length of said telescopic member shall change from normal length when the actuator moves from said one to said second position.

2. In a weft replenishing loom having a plurality of stacks of reserve bobbins and operating with a shuttle to be replenished by bobbins drawn from any one of a group of said stacks and operating also with a second shuttle to be replenished by bobbins drawn from a stack additional to said group, a selector for said stacks movable into register therewith, one at a time, an actuator for the selector occupying one position when one of said shuttles is active and occupying a second position when the second of said shuttles is active, a variable stop operative when said one shuttle is active and said actuator is in said one position and dependent upon the position thereof determining with which stack in said group the selector shall register, and a resilient telescopic member interposed between the actuator and the selector to communicate a force from the actuator to the selector and have the length thereof altered, depending upon the position of the stop, when said one shuttle is active, and said telescopic member operative when the second shuttle is operative to register said selector with said additional stack when the actuator moves to said second position.

3. In a weft replenishing loom having stacks of reserve bobbins and operating with a plurality of shuttles one of which is replenished by bobbins drawn from a group of said stacks and another of which is replenished by bobbins drawn from another stack, a selector for said stacks movable into register with said stacks, one at a time, an actuator for said selector having a given movement from one position when said one shuttle is active to another position when the other shuttle is active, a telescopic connector between said actuator and selector to move the latter by a force derived from the actuator, and a variable stop for said selector operative when said actuator moves to said one position causing said selector to register with different stacks of said group of stacks, dependent upon the position of said stop, and cause different degrees of variation in the length of said telescopic connector, said telescopic connector operative to register the selector with said other stack when the actuator is in said other position thereof.

4. In a weft replenishing loom having a plurality of stacks of reserve bobbins and operating with a shuttle to be replenished from a group of said stacks and operating with a second shuttle to be replenished from another stack not included in said group, a stack selector movable into register with said stacks, one at a time, an actuator occupying one position when said one shuttle is active and occupying the second position when said second shuttle is active, a variable stop having a stop for each stack in said group and mov-

able to present said steps progressively into controlling position, and connections between the actuator and said selector including a part to engage the step in controlling position and including also a resilient member transmitting a force from the actuator to the selector and yielding varying amounts, depending upon which step is in controlling position, when the actuator is in said one position, and said connections and resilient member operative to register the selector with said other stacks when the actuator moves to said second position.

5. In a weft replenishing loom having a group of stacks of reserve bobbins for the replenishment of a shuttle and a selector movable into register with the stacks, one at a time, an actuator for the selector moving to a given position when said shuttle is active, a variable stop for the selector having steps moving progressively to controlling position, and a force transmitting member between the actuator and the selector having two parts movable relatively to each other and a resilient element between said parts, said member having different lengths due to cooperation of said actuator and said variable stop dependent upon which step is in controlling position, and cooperating with the actuator and stop to register the selector with said stacks progressively as the steps move progressively to controlling position.

6. In a weft replenishing loom having a group of reserve bobbin stacks and a stack selector and also having a variable stop for the selector, an actuator for the selector, and a force transmitting means between the actuator and the selector and having a deformable resilient element to transmit a yielding force from the actuator to the selector in cooperation with the variable stop and register the selector with the stacks, one at a time, dependent upon the position of said stop.

7. In a weft replenishing loom having a plurality of stacks of reserve bobbins and a selector movable into register with said stacks, one at a time, and having also an actuator for the selector movable to two positions and a variable stop for said selector, force transmitting means interposed between the actuator and the selector including a deformable element cooperating with the actuator and stop and yielding varying amounts depending upon the position of the stop to cause registry of the selector with any selected stack of a group included in said plurality of stacks when the actuator is in one position thereof and cooperating with the actuator when the latter is in the other position thereof to move said selector out of control of the stop and into registry with another stack additional to the stacks in said group.

8. In weft replenishing loom having a plurality of stacks of reserve bobbins including a group of stacks having similar bobbins and a selector movable into register with all of said stacks, one at a time, and having also an actuator lever for the selector movable to two positions and a variable stop for said selector having steps corresponding to the stacks of said group, a second lever for engagement with the steps of said stop, one stop at a time, and connected to the selector, and a telescopic connector between said levers operative to transmit a yielding force in one direction when the actuator lever is in one position to move the second lever against said stop for determination by said stop of the stack in said group with which the selector shall register and transmitting a positive force in the oppo-

site direction when said actuator lever moves to the other position thereof to effect registry of the selector with a stack outside of said group.

9. In a weft replenishing loom having four stacks of reserve bobbins, three stacks of which form a group all of the bobbins of which are of the same kind, and the fourth stack of which contains bobbins of a different kind, a selector to register with the stacks, one at a time, a three-step cam movable to place the steps thereof progressively in operative position relatively to the selector, an actuator having two positions, and a resilient telescopic connector between the actuator and the selector effective when the actuator is in one position to cause cooperation between the selector and the cam step in operative position to register the selector with the stack of the group corresponding to the step in operative position and operative when the actuator is in the other position thereof to move the selector into register with said one stack.

10. In a weft replenishing loom having three shuttle boxes each movable to active position and provided with weft replenishing mechanism including four stacks of reserve bobbins, the first and second stacks of which have similar bobbins and the third and fourth stacks of which each have distinctive bobbins, said mechanism having a stack selector registerable with the stacks, one at a time, actuator mechanism moving in timed relation with the shuttle boxes and having three positions, one position for each shuttle box, connections between the actuator mechanism and the selector including a resilient telescopic member effective to transmit a yielding force from the control mechanism to the selector tending to move the latter into registry with the first stack when said actuator mechanism is in the first of its positions, effective to move the selector to register with the third stack when said actuator mechanism is in the second of the positions thereof and effective to move said selector into registry with the fourth stack when the actuator mechanism is in the third position thereof, and a stop for the selector movable into and out of stopping position with respect to the selector and when in the stopping position when the actuator mechanism is in the first position thereof causing deformation of said telescopic member to effect registry of the selector with the second stack.

11. In a weft replenishing mechanism having four stacks of reserve bobbins the first and second of which have similar bobbins and the third and fourth of which have distinctive bobbins, the loom having a selector to register with the stacks, one at a time, actuator means including two cams movable to three different relationships, connections between said cams and selector to transmit a force from said cams to the selector tending to move the latter into registry with the first stack when said cams are in one relationship, a telescopic element included in said connections, a stop for said selector movable to two positions and cooperating with the telescopic element to register the selector with either the first or the second stack, dependent upon the position of said stop, when said actuator cams are in said one relationship, resilient means acting on said selector tending to move the latter in registry with the fourth stack but overpowered by said cams when the latter are in their second relationship to cause the selector to register with the third stack, and said resilient means operative when the actuator cams are in their third relationship to register the selector with the fourth stack.

12. In a weft replenishing loom having four stacks of reserve bobbins the first and second of which have bobbins of the same type and the third and fourth of which have bobbins of distinctive type, a selector to register with the stacks, one at a time, a lever having three different positions, a resilient telescopic connector between the lever and selector, and a variable stop for the selector, said lever when in the first position thereof exerting a force through said telescopic connector tending to move the selector in register with the first stack, said stop when in one position registering the selector with the second stack and causing deformation of said telescopic connector and when in another position causing the telescopic connector to register the selector with the first stack, said lever when in the second position thereof transmitting a force through said telescopic connector to the selector to register the latter with the third stack, and the lever when in the third position thereof transmitting a force through the telescopic connector to register the selector with the fourth stack.

13. In a weft replenishing loom operating with three shuttle boxes each of which is capable of being in active position and the loom having four stacks of reserve bobbins, the first and second of which have similar weft corresponding to the first shuttle box and the third and fourth stacks having distinctive wefts corresponding to the second and third shuttle boxes, respectively, two cams moving in timed relation with the shuttle boxes and assuming three different relationships, one for each shuttle box which is in active position, a selector registerable with said stacks, one at a time, connections between said cam means and said selector transmitting a yielding force in one direction corresponding to movement of the selector into registry with the first stack, a spring tending to move said connections in the opposite direction and tending to register the selector with the fourth stack, and a variable stop for the selector movable to two positions, one for each of the first and second stacks, said cams when in their first relationship causing said connections to register the selector with the first stack if said stop is in one position thereof and causing said connections to register the selector with the second stack if said stop is in the other position thereof, and said spring cooperating with said cams when the latter are in their second relationship to cause the connector to register the selector with the third stack, a second stop permanently positioned to limit movement of the selector in a direction away from said first stack, and said spring acting through said connector and cooperating with said second stop independently of the cams to register the selector with a fourth stack when said cams are in their third relationship.

14. In a weft replenishing loom having a plurality of stacks of reserve bobbins and a selector registerable with said stacks, one at a time, a positioner movable positively from a rear position corresponding to registry of the selector with the rearmost stack to a front position corresponding to registry of the selector with the foremost stack, resilient means tending to move said positioner to the rear position thereof, a resilient telescopic connector between the positioner and the selector transmitting a positive force from said positioner to said selector when said resilient means moves the positioner to the rear position thereof, and said telescopic connector being deformable when the positioner moves positively to the front position thereof to permit registry of said selector with any of the stacks other than said rearmost stack.

15. In a weft replenishing loom having a plurality of stacks of reserve bobbins and a selector movable back and forth to register with said stacks, one at a time, a positioner moving positively in one direction, resilient means to move the positioner yieldingly in the opposite direction, and a yieldable connector between said positioner and selector operative to transmit positively a force from said positioner to said selector to cause the latter to register with one of the stacks when said resilient means moves the positioner in said opposite direction, and capable of transmitting a force from said positioner when the latter moves in said one direction to said selector to cause the latter to register with another of said stacks.

16. In a weft replenishing loom having four stacks of reserve bobbins the first and second of which have bobbins of the same type and the third and fourth of which have bobbins of distinctive types, a selector common to the stacks capable of registry with the stacks, one at a time, a controller for the selector having three different positions, a positioner for the selector having two positions, one for each of said first and second stacks, connections between the controller and selector to register the latter with the third and fourth stacks when the controller is in the second and third positions thereof, respectively, said positioner effective to register the selector with either the first or second stack, depending upon the position of said positioner, when the controller is in the first position thereof, mechanism to alternate the position of said positioner between the positions thereof when the controller is in the first position thereof, and means cooperating with said positioner to effect alternate registry of the selector with said first and second stacks when the mechanism alternates the position of said positioner and while the controller is in the first position thereof.

CLIFFORD DARWIN.
